UNITED STATES PATENT OFFICE.

BENJAMIN LIPPER AND ALFRED A. COURTS, OF PHILADELPIIA, PENNSYLVANIA, ASSIGNORS TO AUGUSTUS A. LAZARUS, ISAAC A. SCHWARZ, AND BENJAMIN LIPPER, OF SAME PLACE.

DESIGN FOR A DRESS-TRIMMING.

SPECIFICATION forming part of Design No. 21,677, dated July 5, 1892.

Application filed June 8, 1892. Serial No. 435,997. Term of patent 3½ years.

To all whom it may concern:

Be it known that we, BENJAMIN LIPPER and ALFRED A. COURTS, both citizens of the United States, and residents of Philadelphia, Pennsylvania, have invented a new and original Design for a Dress-Trimming, of which the following is a specification.

Our design is fully shown in the accompanying drawing, which represents a face view 10 of a piece of the trimming.

The trimming has two tape-like bands or ribbons *a a*, between which is a narrow central band *b*, and adjacent to each of the outer edges of the bands *a a* is a narrow band *d*.

15 Projecting beyond each edge of the trimming is a fan-like figure *f*, composed of looped cords, and extending across each of the bands *a a* is a cord *g*, which forms loops *i*, overlap-

ping said band *a* and projecting inward first from one edge of the band and then from the 20 opposite edge of the same. Each cord *g* crosses one of the outer bands *d* of the trimming, and both cords cross the central band *b*.

We claim—

The design for a dress-trimming, substantially as described, and as shown in the accompanying drawing.

In testimony whereof we have signed our names to this specification in the presence of two subscribing witnesses.

BENJAMIN LIPPER.
ALFRED A. COURTS.
